UNITED STATES PATENT OFFICE.

WILLIAM J. SHORT, OF HEBER SPRINGS, ARKANSAS.

AUTOMATIC CARBURETOR ADJUSTMENT.

Application filed November 7, 1923. Serial No. 673,397.

The object of my invention is to provide means for the automatic regulation of the supply of fuel to the carburetor of an explosive engine which will regulate the quantity to suit the engine temperature which will be efficient, simple of construction and convenient of application to the engine. By my invention the temperature of the exhaust gases in passing through the exhaust 5 determines the quantity of fuel supplied to the carburetor by automatically turning the needle valve of the carburetor. My invention consists in whatever is described by or is included within the terms or scope 10 of the appended claims.

In the annexed drawings:

Fig. 1 is a plan view illustrating an embodiment of my invention;

Fig. 2 is a cross section on the line 5—5 20 of Fig. 1;

Fig. 3 is a section on the line 6—6 of Fig. 4.

In the embodiment of my invention shown in Fig. 1 I utilize the longitudinal 25 expansion and contraction of the exhaust pipe due to the passage of the exhaust gases therethrough to impart movement to a connection between the pipe and the needle valve.

By the construction shown in Fig. 1 the use of two long operating rods is avoided and the motion of the exhaust pipe under changes in temperature is magnified when applied to the carburetor valve and the 30 carburetor valve may be adjusted by hand if need be without hindrance from the automatic turning device.

Describing the construction in detail, a collar, 150, is clamped to the exhaust pipe 40 near the muffler and from it extends forward a single rod, 21, which at its forward end is pivoted to a lever, 22, which at mid-length is pivoted to a stud, 23, on a clamp, 24, which is attached to the main frame or 45 chassis and to the lever, 22, on opposite sides of its pivot are pivoted two rods, 25, which extend forward to and pivotally engage a block or yoke, 26, which is held friction tight on the stem, 27, of the needle 50 valve, the pivotal connection between the rods, 25, and said yoke being on opposite sides of the valve stem. The yoke, 26, preferably engages a brass bushing, 28, around the valve stem and said yoke has a 55 radial slit so that by a longitudinal bolt, 26^a, passing across the slit it may be at-

tached with desired friction grip to the bushing so that while such grip is sufficient to enable the movements of the rods, 25, to turn the needle valve, there will be 60 enough slip to allow the turn of the valve by hand should hand adjustment be required. As the points of connection of the rods, 25, with the lever, 22, are a greater 65 distance from the lever point than the point of connection with rod, 21, therewith the movement of the exhaust pipe under changes of temperature when applied to the needle valve will be magnified.

If desired the bushing may be made 70 slightly tapering and screwed into the hole in the yoke, 26, it having a wrench engaging shoulder, 30, to turn and the bushing at its inner end engages packing, 29, of asbestos or other material that encircles the 75 stem within the yoke hole, and thereby is squeezed against the stem to produce a desired friction grip on the stem.

To limit or prevent too great an expansion of the exhaust pipe as in extremely 80 hard pulling which might reduce the fuel too much I provide a stop which consists of an arm, 31, that is secured by a clamp, 32, to the frame or chassis, 140, (see Fig. 1) in position to engage the collar, 150, on 85 the exhaust pipe E². The exhaust pipe will have sufficient lateral spring to take up or allow for longitudinal expansion when stop acts.

What I claim is:

1. The combination of a carburetor valve and the pipe extending from the exhaust manifold of an internal combustion engine, such pipe being free to move longitudinally under temperature changes due to exhaust 95 gases passing through such pipe, a device connected with and partaking of such longitudinal movement of said pipe, the point of connection between said device and the pipe being a substantial distance from the 100 exhaust manifold and the carburetor valve, and an operative connection between said device and the carburetor valve for transmitting to the valve the longitudinal movement of the exhaust pipe and said operative connection comprising means to multiply the motion transmitted from the exhaust pipe. 105

2. The combination of a carburetor valve and the exhaust pipe of an internal combustion engine, such exhaust pipe being free to move longitudinally under temperature changes due to exhaust gases passing 110

- through such pipe, a device connected with and partaking of such longitudinal movement of the exhaust pipe, the point of connection between said device and exhaust pipe being a substantial distance from the carburetor valve, and an operative connection between said device and the carburetor valve for transmitting to the valve the longitudinal movement of the exhaust pipe, such connection situated to be substantially unaffected by heat from the exhaust pipe and said operative connection comprising means to multiply the motion transmitted from the exhaust pipe consisting of a lever and its pivot and a movable member engaging the lever at different distances from the lever pivot, the lever moving member being nearer the pivot.
3. The combination of a carburetor valve and the exhaust pipe of an internal combustion engine, a device clamped to said pipe remote from the carburetor valve, a lever mounted nearer to the valve than said clamp, a pair of rods extending from said lever on opposite sides of its center of motion to the carburetor valve on opposite sides of its center of motion and a single rod extending from said lever to said clamp.

4. The combination with a carburetor valve and a thermostat for moving the latter comprising the exhaust pipe of an internal combustion engine free to move longitudinally when affected by the temperature of gases passing through the same, and means to limit such movement of the exhaust pipe.

5. The combination of a carburetor valve and the pipe extending from the exhaust manifold of an internal combustion engine, such pipe being free to move longitudinally under temperature changes due to exhaust gases passing through such pipe, a device connected with and partaking of such longitudinal movement of said pipe, the point of connection between said device and the pipe being a substantial distance from the exhaust manifold and the carburetor valve, and an operative connection between said device and the carburetor valve for transmitting to the valve the longitudinal movement of the exhaust pipe, said connection permitting independent movement of the valve by hand.

In testimony whereof I hereunto affix my signature.

WILLIAM J. SHORT.
